UNITED STATES PATENT OFFICE.

CHARLES A. KNOWLTON, OF ERIE, PENNSYLVANIA, ASSIGNOR TO THE AMERICAN STOKER COMPANY, OF ERIE, PENNSYLVANIA, A CORPORATION OF NEW YORK.

STOKER.

No. 867,979.

Specification of Letters Patent.

Patented Oct. 15, 1907.

Application filed February 11, 1904. Serial No. 193,169.

To all whom it may concern:

Be it known that I, CHARLES A. KNOWLTON, a citizen of the United States, residing at Erie, in the county of Erie and State of Pennsylvania, have invented new and useful Improvements in Stokers, of which the following is a specification.

This invention relates to stokers and consists in certain improvements in the construction thereof as will be hereinafter fully described and pointed out in the 10 claims.

The invention is illustrated in the accompanying drawings as follows:

Figure 1 shows a section on the line 1—1 in Fig. 2. Fig. 2 shows a section on the line 2—2 in Fig. 1. Fig. 15 3, a front elevation of a furnace. Fig. 4, a detached plan view of a grate carriage construction showing the rear end of said construction. Fig. 5, is a section on the line 5—5 in Fig. 4, the grate bars being removed to better show construction. Fig. 6 is a perspective view 20 of a grate bar. Fig. 7, a perspective view of a part of the twyer cap. Fig. 8, a detailed view of the rock lever for operating the grate carriages. Fig. 9, a detailed view of the track for the grate carriage rollers. Fig. 10, a side elevation of one of the grate carriage rollers. Fig. 25 11, an end elevation of the same. Fig. 12, a detailed view of one of the sides of one of the grate carriages. Fig. 13, a detailed view of one of the sides of the companion grate carriages.

I have shown my invention as adapted to an under 30 feed stoker arranged at the center of a furnace. A marks the furnace; A' the bridge wall; A² the ash pit; A³ the front wall; B, a fragment of a boiler mounted over the furnace. These are of ordinary construction.

The feed device to which I have attached my invention is not in itself new. It comprises the feed box C which extends longitudinally into the furnace from a point without the same. Arranged in the box is the conveyer screw C'. This screw is mounted on the shaft C². A hopper C³ opens into the feed box C and fuel is delivered to this hopper and carried by the conveyer screw into the furnace, and forced up over the top of the box. The screw is operated by an engine of which the cylinder G forms a part. The link g extends from the piston rod (not shown) of the engine. 40 The rock arm g' is connected with the link g; the pawls g² are arranged on the rock arm. The ratchet wheel g³ is in the path of the pawls g². It will readily be seen that as the engine reciprocates the shaft C² is rotated through the action of the levers g' and g² upon the 45 ratchet wheel, thus driving the screw conveyer and effecting the feed.

This style of stoker and feeding device has been actively on the market for some time. The wind box D is arranged immediately under the feed box, and air

passes from the wind box into the furnace through the 55 twyer f in the twyer cap F. Supplemental twyers E are arranged below the cap. In practice it has been found that with some fuels at least there has been some difficulty with clinkers forming at the edges of the feed box, and also in carrying away the clinkers and 60 ash from the sides of the feed box after it is fed into the furnace. My invention is especially adapted to this arrangement of feed mechanism, but is not so limited or in fact to a use with any specific mechanism, in as much as the feed may be delivered directly to the grate 65 bars without the intervention of a special feeding device.

The grate bar mechanism is provided with carriages having the side pieces J and J' (see Fig. 5.) These are carried by the rollers I and I'. The rollers are mounted 70 on the tracks H. The side pieces J are connected by the cross pieces j² and j⁴, and the side pieces J' are connected by the cross pieces j³. The side pieces are provided with the roller surfaces j and j', and the tracks H are provided with the roller surfaces h and h'. The 75 rollers I and I', as clearly shown in Figs. 10 and 11, are adapted to roll on these surfaces, the flanges i of the rollers extending each side of the surface and keeping the rolls in place on the track and the carriages in place on the roller. The cross pieces are in the form of T 80 irons and the grate bars K are simply placed on the uprights of these cross pieces, the grate bars having channels k for this purpose. The grate bars are preferably provided with the shoulder k', for engaging the fuel and to better adapt them for feeding the fuel forward. The two carriages are reciprocated in opposition, that is they are moved in opposite direction so that the grate bars carried by one carriage are moved in an opposite direction from that of the grate bars carried by the other carriage, thus breaking up any clinker 85 90 that may be deposited on the grate bars in feeding the fuel forward. The grate bars are stepped so that each grate bar passes over the next succeeding grate bar below it. With the straight line parallel movement thus afforded the grate bars may be moved much closer together than commonly, and therefore have a greater efficiency both as to the removing of clinker from the bars, and also in making a closure between the furnace and the ash pit. The roller bearings eliminate friction, and at the same time form a bearing which will be efficient 95 even though the parts be distorted to considerable extent by heat.

In the feeding device here shown some difficulty has been experienced in keeping the twyer cap free from clinker and from burning out. I prefer therefore to arrange the twyer cap on the cross piece j⁴ so that it gets the movement of the grate bars, thus clearing it to a large extent of clinker and relieving it of the difficulty 100 105

mentioned. Immediately below the twyer cap I provide the stationary bar L over which the twyer cap moves. It is arranged immediately over the top of the wind box and forms a part of the twyer system.

- 5 I have provided a preferable mechanism for reciprocating the grate carriages. It is especially efficient in connection with the screw conveyer herein described. The gear g^4 is fixed on the shaft C². This drives a gear m^2 . The gear m is fixed on the shaft M. The shaft M extends through the wind box to the rear-end of the ash pit where it is journaled in the box M². An eccentric M' is fixed on this shaft near the rear end thereof and operates in a yoke N. The links n extend from the yoke N to the rock levers O. The rock levers O are fixed on the shafts O' and arranged near the rear ends thereof. These shafts are journaled in the boxes O³ and O⁴ and extend along the sides of the wind box to the front of the furnace. Rock levers O², similar in construction to the rock levers O are arranged on the front ends of these shafts O'. The carriage sides J and J' are provided with the slots j⁶ and j⁷. The pins o extend from the rock levers into the slots j⁷ and the pins o' extend into the slots j⁶ and communicate the movement of the levers to the carriages. It will readily be seen that as the rock levers are moved through the action of the eccentric the carriages are moved in opposite directions, thus carrying the grate bars of one carriage over the grate bars of the other carriage. It will also be noted that the carriages J at both sides of the feed device move in the same direction so that the twyer construction may be made in one piece. At the side of the furnace I provide the passage P for ashes and clinker. In order to prevent the entrance of cold air at this point I make the wall of this passage in cylindrical form and introduce the winged gate p. This gate is mounted on the shaft P'. It will readily be seen that while the turning of this shaft will carry any deposit on the wings p' through the passage P it closes the passage P at all times to the passage of air. A lever P² is arranged at the front of the furnace for turning the gate p.

While I have shown the mechanism with the removable grate bars I do not wish to be understood to so limit the structure.

- 45 The grate bars may form if desired a part of the carriage frame and the carriage frame sides may if desired be formed integral with the grate bars.

What I claim as new is:—

1. In a stoker the combination of a feeding device for carrying fuel from without the furnace to within and along the interior of the furnace in a longitudinal direction relatively to the furnace; grates arranged at the sides of the feeding device; carriages for supporting the grates;

rollers for supporting the carriages laterally with respect to the direction of movement of the fuel in the feeding device; and means for reciprocating the carriages. 55

2. In a stoker the combination of a feeding device for carrying fuel from without the furnace to within and along the interior of the furnace in a longitudinal direction relatively to the furnace; grates arranged at the sides of 60 said feed device; carriages for supporting said grates, the grate bars being arranged on said carriages in groups said groups comprising alternate grate bars; rollers for supporting the carriages; and means for reciprocating the carriages in opposite directions to move the grate bars of 65 the groups supported thereby in opposite directions.

3. In a stoker, the combination of a feed box arranged to deliver fuel from beneath the fire; a fuel support in the form of a twyer cap for said box; a grate arranged at the side of said twyer cap and adapted to carry fuel from said 70 cap; said grate comprising reciprocating grate bars; a carriage for supporting said reciprocating grate bars; rollers for supporting said carriage; and means for reciprocating said carriage laterally relative to the direction of feed through the feed box.

4. In a stoker, the combination of a feed box arranged to deliver fuel from without the furnace to within and along the interior of the furnace and from beneath the fire; a fuel support in the form of a twyer cap for said box; a grate comprising grate bars arranged in groups and adapted to move the fuel laterally from said box; a carriage for each group; rollers for supporting said carriages; and means for reciprocating said carriages in opposite directions, the grates being arranged to carry the fuel from the feed box laterally across the furnace. 80

5. In a stoker the combination of a feed box arranged to feed fuel from beneath the fire; a fuel support in the form of a twyer cap at the side of said feed box adapted to receive the fuel from said box; grate bars arranged at the sides of the twyer cap and adapted to receive fuel 90 therefrom; a carriage for supporting said grate bars and the twyer cap; rollers for supporting said carriage; and means for reciprocating said carriage and with it the grate bar and twyer cap. 95

6. In a stoker, the combination with the grates extending from front to rear of the stoker, of carriages supporting said grates, a shaft extending from the front of the stoker to the rear of the stoker, operating means arranged on the shaft at the rear of the stoker for moving said carriages, mechanism transmitting the movement of said operating means to the front of the stoker, and means at the front of the stoker connecting said mechanism with the carriages. 100

7. In a stoker the combination with the grate; of carriages for said grate; the rock shaft O' having the rock levers O and O² thereon; connections between said rock levers and said carriages for reciprocating said carriages in opposite directions; and means connecting with the rock lever O at the rear of the stoker for actuating the rock shaft O'. 110

In testimony whereof I have hereunto set my hand in the presence of two subscribing witnesses.
